FREDERIK SCHADE, OF COPENHAGEN, DENMARK.

METHOD AND MACHINE FOR THE PRODUCING OF TIGHTLY-COILED PAPER.

Application filed February 9, 1927, Serial No. 166,889, and in Denmark February 9, 1926.

Hitherto it has not always been possible to obtain a tight coiling-up of webs of paper if these consist of fragile paper, or of paper of unequal thickness along its two edges, or 5 which, in order to reduce to a minimum the width of the paper coil, consist of a plurality of layers of folded paper or, for example, coils of paper with one or a plurality of linings. Coils of such paper have 10 hitherto been made in the form of "loose coils", i. e. having the single convolutions or windings loosely contacting with each other.

According to the method constituting the 15 object of the present invention a tight coiling-up can be performed of the said paper web. The method consists in tightening the windings from inside and not, as is usual, from outside, there being at the same time 20 exerted an axial pressure on the end surfaces of the coil of paper under formation. This pressure is exerted by means of plates, discs, rods or the like disposed at right angles to the axis of the coil. The tightening-up of the single windings of the coil is 25 then performed by means of the friction produced between the edges of the single windings and the members exerting the axial pressure. Each winding is thus prevented 30 from moving until the pull exerted thereon from the windings already tightly coiled-up has reached such a magnitude that it is able to overcome the said friction. One after the 35 other of the windings will thus be placed tight on the core already formed so that gradually a tight coil will be formed even if the paper web is very fragile or difficult to treat.

The members exerting the axial pressure 40 do not partake in the rotary movement of the coil. The said members are adapted to be slid along the rotating shaft carrying the paper coil and the sliding movement may be performed, for example, by means of a 45 frame provided with movable end pieces engaging said members which are provided at both ends of the coils. It will suffice if one of said members is movable in the axial direction.

50 The invention is illustrated in the drawing where

Fig. 1 shows in top view a part of the machine,

Fig. 2 is a section through a web of paper 55 the outer portions of which have been folded

and which has subsequently been cut through along its central line,

Fig. 3 shows a top view of a device with a shaft serving for coiling-up a paper web, 60 Fig. 4 is a side view of said device, and Fig. 5 is a section, on a larger scale, through a shaft to which one end of a paper web has been secured.

On the drawing 1 indicates a paper coil 65 consisting of a web of paper having two folds or plies 2 and 3 (Fig. 2). The coil is located on a shaft 4 adapted to be rotated by means of a pulley 5 and carrying another pulley 6 which through a belt 7 rotates a pulley 8. The pulley 8 is secured to a shaft 70 9 which through a coupling device is connected to a shaft 11 suitably journaled and carrying two discs 12 slidable in an axial direction and having holes into which rods 13 may be passed. An intermediate disc 14 75 is provided on shaft 11 between the two discs 12.

If the coil 1 consists of double-folded paper as shown in Fig. 2 there will, when the conditions are suitably adjusted, be 80 wound on shaft 11 two adjacent webs of paper, as a rule one on either side of the intermediate disc 14, a knife, not shown on the drawing, being located in front of the latter for cutting through the wide, double-folded web of paper running off from the coil.

The two discs 12 may be provided with relatively wide hubs 15 adapted to slide 85 along the shaft 11 and to be secured in any desired position on the latter, for example, by means of screws 16 or the like.

The two discs 12 and the intermediate disc 14 are provided with holes registering 90 with each other and through said holes (three in each disc) there may, as mentioned above, be passed rods 13 which fit snugly in the holes so that the discs may be readily moved in both directions.

The free end of the paper web of the coil 1 100 is secured to the shaft 11 as shown in Fig. 5. Shaft 11 has an axially disposed groove 17 into which there may be driven a wedge 18 around which the paper strip has been folded.

During the operation of the machine the paper web is wound up from coil 1 into two coils on shaft 11 or on the rods 13. If the rotation of shafts 4 and 11 is properly adjusted the paper web will be wound relative- 110

ly loose on shaft 11. When a suitable number of layers have been wound on said shaft or on the rods 13 the machine is stopped and the shaft 11 with the loosely wound paper is removed to two bearings 10 (Fig. 3) located near by and in which the shaft fits. One end of shaft 11 carries a square pin 19 adapted to be connected to a shaft 20 by means of a coupling member 21 slidable along the ends of said shafts 11 and 20. Adjacent the bearings 10 there is provided a rod 22 parallel to the axis of said bearings and around which a frame 23 comprising two members may be swung up or down (see Fig. 4). Each member 23 carries on its under surface a fork 24 adapted to engage discs 25 centrally located on the outer surfaces of the two discs 12. The members 23 will, consequently, rest on shaft 11 and the forks 24 will prevent the discs 12 from rotating due to the discs 25 having an oblong shape as shown.

Threaded rods 26, 27 on either side of shaft 11 pass through threaded holes in said members 23, which rods are interconnected by means of a chain 28 or the like. The rod 27 is further provided with a hand wheel 29. On the hand wheel being rotated the members 23 and thereby the discs 12 will be moved towards each other.

On the shaft 20 being rotated, shaft 11 in the bearings 10 will thereby be rotated. The said shaft 11 carries the loosely wound coil of paper.

The hubs 15 and the discs 12 are, as mentioned above, secured in position by means of the forks 24, whilst shaft 11, to which the ends of the two webs of paper are secured, is rotating and produces the tightening of the coils from inside. When hand wheel 29 is rotated both screw-rods 26, 27 are rotated simultaneously by means of chain 28 so that their threads, operating in the threaded holes of the discs 12, move the latter axially on the shaft 11. The movement of the discs 12 towards disc 14 cause a pressure against the sides of the two coils wound on the shaft 11, which pressure may be regulated according to the degree of axial movement of the discs 12. The latter being held against rotation by the forks 24 engaging the hubs 25, as described above, and the shaft 11 being rotated, the inner end of the web forming the center of the roll and secured to said shaft moves with the latter while the remaining convolutions of the web forming the outer portion of the roll are prevented from moving at the speed of the shaft. The tightening of the winding of the coil thus takes place from the inside during the formation of the roll and is due to the frictional resistance produced between the stationary discs 12 and the end surfaces of the slower rotating coils of paper. Due to the axial pressure of the discs 12 on the loosely coiled paper the roll of paper will not rotate with the shaft 11 and the

latter will therefore wind the web of paper tightly upon itself from the inside.

When the finished coils are to be removed, the members 23 together with the corresponding discs 12 are detached. When the wedge 18 is subsequently removed from shaft 11 the latter can be readily pulled out of the coil.

The rods 13 must be removed from the discs 12 before the tightening operation is initiated.

It is not imperative to move shaft 11 into the bearings 10 for the performing of the tightening operation which latter can very well be performed by means of the machine shown in Fig. 1. In this case, however, the speed of the machine must be adjustable so as to become suitably slow during the tightening operation. A plant comprising one machine of the kind shown in Fig. 1 and a plurality of the kind shown in Fig. 3 will therefore prove more economical.

The plate 14 located on shaft 11 between the two discs 12, prevents the adjacent end surfaces of the two coils on shaft 11 from sliding on one another during the rotation of the shaft which would otherwise result in their tearing one another.

I claim:

1. The method of producing tightly wound rolls of paper, which comprises coiling one end of the paper web on a rotating core of fixed diameter to form a compact central portion, and exerting lateral pressure on both edges of the outer convolutions of the web to retard the rotation of the outer convolutions until the pull exerted by the compact central portion of the web is sufficient to overcome said lateral pressure.

2. In a machine for producing tightly wound rolls of paper, a rotatable shaft on which the web of paper is coiled, laterally arranged pressure members adapted to engage both edges of the roll on said shaft, means to axially move one of said members relatively to the roll, and means to lock the axially movable member against rotation.

3. In a machine for producing tightly wound rolls of paper, a rotatable shaft on which the web of paper is coiled, discs slidably mounted on the shaft at opposite ends of the roll, means for moving the discs axially of the shaft into and out of engagement with the roll on the shaft, and means to lock the discs against rotation.

4. In a machine for producing tightly wound rolls of paper, a rotatable shaft on which the web of paper is coiled, discs slidably mounted on the shaft at opposite ends of the roll, laterally movable members for locking the discs against rotation, and means for simultaneously moving said members axially of the shaft to impart axial movement to the discs.

5. In a machine for producing tightly

- wound rolls of paper, a rotatable shaft on which the web of paper is coiled, pressure discs slidably mounted on the shaft at opposite ends of the roll, pivoted frame members 5 engaging the discs and adapted to lock the latter against rotation, and means for simultaneously moving the frame members in opposite directions axially of the shaft to impart axial movement to the discs.
- 10 6. In a machine for producing tightly wound rolls of paper, a rotatable shaft on which the web of paper is coiled, pressure discs slidably mounted on the shaft at op-

posite ends of the roll, a frame having side bars pivotally mounted parallel to the discs, 15 forks on said side bars for locking the discs against rotation, transverse rotary adjusting rods in threaded connection with said side bars, and means for operatively connecting the rods together for simultaneously 20 rotating the latter to impart axial movement to said bars and discs.

In testimony that I claim the foregoing as my invention, I have signed my name.

FREDERIK SCHADE.
